[57] ABSTRACT

A microampere current source for an integrated circuit comprising a first d-c current source for providing an input control current of at most 10 μ A, first and second semiconductor circuits having substantially equal emitter characteristics, a resistor coupled to said first and second semiconductor circuits to form a closed loop and a second d-c current source coupled to the loop. The first semiconductor circuit comprises a rectifier and is coupled to the second semiconductor circuit so as to provide for the passage of the input control current through the base-emitter path of the semiconductor circuits. The second d-c current source provides a reference potential to the emitter of the second semiconductor circuit and supplies a current to the resistor of such magnitude that the voltage drop across the rectifier exceeds the base-emitter voltage of the second semiconductor circuit by between 20 and 540 millivolts.

MICROAMPERE CURRENT SOURCE

This is a continuation, of application Ser. No. 100,205, filed Dec. 21, 1970, and now abandoned.

The invention relates to a microampere current source for an integrated circuit, in which from a control direct current of the order of 10 microamperes or less an attenuated direct current is derived, the control direct current flowing through a first circuit which includes a rectifying junction, while the attenuated direct current flows through the emitter collector path of a transistor the base emitter path of which has been included in a second circuit having the same pass direction and has been connected parallel to the aforementioned circuit, a substantially signal-free direct current for at least one transistor of the integrated circuit being derived from the collector of the aforementioned transistor, a resistor having been included in the closed loop constituted by the two parallel circuits.

A known microampere current source of this type includes a transistor which is connected as a diode in parallel with the series combination of the base emitter of another transistor and a resistor. The input current to be attenuated is supplied to the diode, the attenuated output current being taken from the collector of the transistor. The attenuation factor α is adjusted by means of the resistor, α being equal to the ratio between the output current and the input current. The resistor is determined by the following expression:

$$R = kT/q \cdot 1n\alpha/i \quad (1)$$

In this expression R is the value of the said resistor, T is the temperature of the microampere current source in degrees Kelvin, q the unit charge of an electron and i the output current. The above expression (1) clearly shows that the value of the resistor R must be very large if a very small output current i is required. Thus, it can be computed by means of the said expression that if, for example, starting from an input current of 10 microamperes an output current of 0.1 microampere is desired, a resistor of 1.2 megohm is required. Such a resistor cannot be made in integrated form.

Another known microampere current source of the said type includes a transistor which is connected as a diode in parallel with the base emitter diode of another transistor. The input current to be attenuated is supplied to the diode and the attenuated output current is taken from the collector of the second transistor. In this known microampere current source, the attenuation factor by which the input current must be attenuated to obtain the output current is adjusted by means of the ratio between the effective emitter surface area of the transistor connected as a diode and the effective emitter surface area of the base emitter diode of the second transistor. This arrangement has the disadvantage that an increase in the desired value of α requires a relatively increased emitter area of the diode for the integrated circuit.

It is an object of the present invention to provide a solution of the aforementioned problems, and a microampere current source according to the invention is characterized in that the emitter of the second transistor has been connected to a point of constant potential by way of a current source which supplies to the resistor a current such that the voltage drop across the recti-

fying junction exceeds the voltage drop across the base emitter diode of the transistor by at least 20 millivolts and at most 540 millivolts.

An embodiment of the invention will now be described, by way of example, with reference to the accompanying diagrammatic drawings, in which:

FIG. 1 shows an embodiment of a microampere current source according to the invention,

FIG. 2 shows an example of the use of such a microampere current source, and

FIG. 3 shows another example of the use of the microampere current source according to the invention.

The microampere current source shown in FIG. 1 comprises a transistor T_1 , a transistor D_1 connected as a diode, current sources S_1 and S_2 and a resistor R . The base of the transistor T_1 is connected through the transistor D_1 to the negative terminal of a voltage supply source E and also, through the input current source S_1 , to the positive terminal of the said voltage supply source E . The emitter of the transistor T_1 is connected through the resistor R to the negative terminal of the supply voltage source E and also, through the current source S_2 , to the positive terminal of said voltage supply source E . The output current can be derived from the collector of the transistor T_1 .

The operation of the microampere current source according to the invention is as follows: It is assumed that it is desired to have an output current i_0 which is smaller than the input current i_1 by a factor α , i.e., $i_1 = \alpha \cdot i_0$. By way of example, i_1 may be equal to $10\mu\text{A}$, and i_0 to $0.1\mu\text{A}$ and hence $\alpha = 100$. In addition, R is required to be at most equal to 5,000 ohms. The voltage across the diode D_1 is equal to: $V_{D1} = kT/q \cdot 1n(i_1/i_{10})$

where i_1 is the input current and i_{10} the intrinsic leakage current of the diode D_1 . The voltage across the base emitter diode of the transistor T_1 is equal to: $V_{B1} = kT/q \cdot 1n(i_0/i_{00})$ (3)

where i_0 is the output current and i_{00} is the intrinsic leakage current through the transistor T_1 . If the effective emitter surface area of the transistor is equal to the effective emitter surface area of the transistor D_1 connected as a diode, the voltage across the resistor R is expressed by:

$$V_R = kT/q \cdot 1n(i_1i_0) = kT/q \cdot 1n\alpha \quad (4)$$

With respect to the example chosen, a simple computation shows that V_R must be equal to 120 millivolts. This means that the current i_2 to be supplied by the current source S_2 must at least be equal to 24 microamperes at $T = 300^\circ\text{K}$.

FIG. 2 shows the use of the microampere current source in a differential amplifier. The differential amplifier comprises transistors T_6 to T_{11} . The signal to be amplified is applied to the bases of the transistors T_6 and T_{11} . The collectors of the transistors T_6 , T_7 , T_{10} and T_{11} are directly connected to the positive terminal of the supply voltage source E . The collectors of the transistors T_8 and T_9 are connected to the positive terminal of the voltage supply source E through transistors T_{13} and T_{12} respectively. The base emitter paths of the transistors T_{11} , T_{10} and T_9 and of the transistors T_6 , T_7 and T_8 are connected in series, the emitters of the transis-

tors T_8 and T_9 being connected to one another. Transistors T_1 through T_5 form parts of a multiple microampere current source, which further comprises the current source S_2 , the diode D_1 and resistors R and R_8 . The current source S_2 includes a differential amplifier V the output of which is connected to the base of a transistor T_{14} . A current i_2 is taken from the emitter of the transistor T_{14} and supplied to the resistor R of the multiple microampere current source. The collector of the transistor T_{14} is connected to the positive terminal 10 of the voltage supply source E through a resistor R_4 and also to the base of the transistor T_{15} connected as an emitter follower. The emitter of the transistor T_{15} is connected to an input of the differential amplifier V and also, through the series combination of resistors R_5 and R_7 , to the negative terminal of the voltage supply source E . The other input of the differential amplifier is connected to the positive terminal of the voltage supply source through a diode D_2 and also to the negative terminal of the voltage supply source through the series combination of resistors R_6 and R_7 . The bases of the transistors T_1 to T_5 are connected to the positive terminal of the voltage supply source through a resistor R_8 and also to the negative terminal of the voltage supply source through the diode D_1 . The emitters of the transistors T_1 and T_5 are connected to the negative terminal of the voltage supply source through the series combination of resistors R_1 , R_2 and R_3 . The emitters of the transistors T_2 and T_4 are connected to the junction point of the resistors R_1 and R_2 . The emitter of the transistor T_3 is connected to the junction point of the transistors R_2 and R_3 . The operation of the circuit arrangement shown in FIG. 2 is as follows:

The multiple current source is assumed to have to deliver the following output currents:

$$i_{01} = i_{05} = 0.3 \times 10^{-9} \text{ ampere},$$

$$i_{02} = i_{04} = 6 \times 10^{-9} \text{ ampere}$$

$$i_{03} = 240 \times 10^{-9} \text{ ampere}$$

If we assume an input current $i_1 = 0.3 \times 10^{-3}$ ampere and a supply voltage of 3 volts, the resistor R_8 will have to be equal to 8,000 ohms and hence may readily be manufactured in integrated form. A simple computation shows that the voltage across the resistor R required for small output currents i_{01} to i_{05} will have to be 360 millivolts. The voltage across the sum of the resistors R_2 and R_3 must be 282 millivolts and the voltage across the resistor R_3 must be 204 millivolts. The aforementioned voltages are required at room temperature, that is to say, $T = 300^\circ\text{K}$. If the sum of the resistors R_1 , R_2 and R_3 is about 4,600 ohms, with $R_1 = R_2 = 1,000$ ohms and $R_3 = 2,600$ ohms, the current source S_2 will have to supply a current $i_2 = 70$ microamperes.

If the additional current i_2 were not passed through the resistor R , producing the aforementioned output currents i_{01} to i_{05} would require the resistor R to be about 780 megohms. Such a resistor cannot be made in integrated form and consequently would have to be an external resistor connected to the integrated circuit, so that the latter must have an additional external terminal. Moreover, the large value of the resistor R causes this terminal to be extremely sensitive to external disturbances. Also, the manufacture of resistors of such large values is difficult. Since present-day integrated circuit technology enables pairs of substantially identical transistors, i.e., transistors differing by less than 2

percent to be manufactured, the offset voltage introduced into the differential amplifier by, for example, T_1 and T_5 will be only 0.5 millivolt. A practical embodiment of a differential amplifier required an input current of less than 10^{-11} amperes at an offset voltage of at most 5 millivolts. The current source S_2 supplies a current i_2 according to the following expression:

$$i_2 = 1/R_4 \cdot (kT/q) \cdot \ln(R_5/R_6) \quad (5)$$

where R_4 , R_5 and R_6 are the resistance values of the resistors R_4 , R_5 and R_6 of the circuit arrangement shown in FIG. 2. This expression shows that the said current 15 is a function of the temperature T . According to the expression (4) the attenuation factor is a function of V_R and of the temperature T . When V_R is maintained constant, according to the expression (4) a change of temperature will cause a change of the attenuation factor. 20 The expression (4) further shows that, if the voltage V_R across the resistor R varies directly with kT/q , the attenuation factor α will not change as a function of temperature. This has been achieved by causing the current i_2 according to the expression (5) to flow through the resistor R , assuming the resistors R and R_4 to have equal 25 temperature coefficients. The same effect is obtainable by causing a constant current i_2 to flow through the resistor R and by ensuring that this resistor has a temperature coefficient such that the voltage produced across it will be proportional to kTq .

FIG. 3 shows a second example of the use of a microampere current source according to the invention. In this example, the microampere current source has been connected in the negative feedback loop of an amplifier A. The output of the amplifier is connected to the bases of the transistors T_2 and T_1 . The emitter of the transistor T_2 is directly connected to a point of constant potential, and the emitter of the transistor T_1 is connected thereto through a resistor R . The emitter of the transistor T_1 is also connected to a current source S_2 which supplies a current i_2 . The collector of the transistor T_1 is connected to the input I of the amplifier A. The amplified output signal may be derived from the collector of the transistor T_2 .

45 The inclusion of the microampere current source in the negative feedback loop of the amplifier A ensures a constant current amplification from input to output. When the input current of the amplifier is negligible compared to the collector current of the transistor T_1 , the output current i_1 will be substantially insensitive to 50 variations in the transistor parameters of the transistors of the amplifier A. In addition, variations in the supply voltage of the amplifier substantially do not affect the output current i_1 .

55 What is claimed is:

1. An integrated circuit for providing an attenuated direct current, comprising: a common terminal; a first direct current source for providing an input current to be attenuated; semiconductive rectifying means connected in forward direction between said first current source and said terminal; a transistor having a collector output circuit and a base-emitter path formed for passing current in the same direction as said rectifying means, the base of said transistor being connected to a common point of said first current source and said rectifying means, a second direct current source connected to the emitter of said transistor, a resistor con-

nected between said terminal and a common point of said second current source and said emitter, said resistor having a value corresponding substantially to $kT/q \cdot 1n\alpha/i_2$, where k is Boltzmann's constant, T is the absolute temperature, q is the input charge of an electron, i_2 is the current supplied by the second current source, and α is the attenuation factor, said second current source being connected for passing the current in the same direction as said rectifying means, whereby the attenuated direct current is taken from the collector 10 circuit of said transistor.

2. An integrated circuit as claimed in claim 1, wherein said semiconductive rectifying means is a base-emitter junction of a second transistor having an effective emitter surface area substantially equal to that of said first transistor.

3. A microampere current source as claimed in claim 1, characterized in that the resistor has a positive temperature coefficient, the current supplied by the second D.C. current source being constant.
